UNITED STATES PATENT OFFICE.

AXELL WATTERBERG, OF SANISH, NORTH DAKOTA.

ROTARY ENGINE.

1,227,350.

Specification of Letters Patent.

Patented May 22, 1917.

Application filed October 23, 1916. Serial No. 127,157.

To all whom it may concern:

Be it known that I, AXELL WATTERBERG, a citizen of the United States, and a resident of Sanish, in the county of Mountrail 5 and State of North Dakota, have invented a new and Improved Rotary Engine, of which the following is a full, clear, and exact description.

My invention relates to a rotary engine 10 of the multicylinder type. The object is to provide a reversible engine which is simple and efficient.

With the above and other objects in view, the nature of which will more fully appear 15 as the description proceeds, the invention consists in the novel construction, combination and arrangement of parts as herein fully described, illustrated and claimed. In the accompanying drawings, forming part 20 of the application, similar characters of reference indicate corresponding parts in all the views.

Figure 1 is a front elevation of the engine, the housing and tubular shaft being 25 in section on line 1—1, Fig. 2;

Fig. 2 is a vertical, axial section of the engine on line 2—2, Fig. 1;

Fig. 3 is a transverse vertical section of the engine on line 3—3, Fig. 2;

Fig. 4 is an enlarged sectional view on line 4—4, Fig. 2;

Fig. 5 is a similar section on lines 5—5, Fig. 2;

Fig. 6 is an enlarged transverse section 35 on line 6—6, Fig. 2;

Fig. 7 is a similar section on line 7—7, Fig. 2;

Fig. 8 shows the position of the valve when the engine is reversed; and

Fig. 9 shows the cut-off control displaced to vary the expansion of the motor fluid in the engine.

Referring to the drawings, 10 is the valve casing which is mounted on a tubular shaft 45 11 to revolve therewith. The shaft is revolvably mounted in bearings 12 which are carried by standards 13 of the engine base, which is not shown. Each bearing has an eccentric 14 on which a strap 15 is mounted 50 to revolve. The strap carries rollers 16 which bear on the periphery of the eccentric 14.

The valve casing 10 carries a plurality of cylinders 17 extending radially therefrom. 55 A piston 18 is provided in each cylinder,

the rod 19 thereof projecting through the cylinder head 20. Each rod terminates in a crosshead 21 connected to the eccentric straps 15 by connecting rods 22. Guides 23 are provided on each cylinder head for 60 the corresponding crosshead. The pins 24 which connect the crossheads to the eccentric strap each carry a roller 25. Each roller 25 is maintained against an independent circular track 26, the diameter of which track 65 is equal to the piston displacement plus the diameter of roller. The four tracks on each side have the same angular relation as the cylinders. They are formed in a unitary member which is constrained to revolve with 70 the tubular shaft.

A tubular valve 27 is provided in the valve casing 10, said valve extending through the tubular shaft 11. The projecting end of said valve passes through the head 28 of a 75 conduit 29 through which motive fluid is supplied to the valve 27 where it registers with the head of the conduit 29. Suitable packings 30 seal the head 28 of the valve 27. The valve 27 has inlet passages or ports 80 31 and 32. The port 31 registers with passages 33 in the valve casing when said casing revolves. These passages 33 are connected to corresponding cylinder heads 20 by conduits 34 through which motive fluid 85 is admitted to the outer ends of the cylinder. The port 32 registers with passages 35 in the valve casing which lead directly to the adjacent or inner ends of the cylinders and through which the motive fluid is 90 admitted to said cylinder ends. The valve 27 has also exhaust ports 36 and 37 separated from the admission ports 31 and 32 by a partition 38. The ports 36 and 37 register with passages 39 and 40 respectively 95 in the valve casing when the valve casing revolves. From there the gases have a free egress through the tubular shaft 11 which has openings registering with a head 56 of a conduit 55. The passages 40 are connected 100 to the heads 20 of the corresponding cylinders by conduits 41.

The valve 27 is provided with an arm 42 whereby the valve may be turned within the valve casing to advance or retard the registration of the passages of the valve casing with the ports of the valve. As shown in Figs. 4 and 6, steam will be admitted to the cylinder above and below the horizontal plane after the cylinders have passed the 110

vertical; therefore the application of the force for rotation of the engine will begin past the dead center. The exhaust from the engine takes place, as will be noted from Figs. 5 and 7, slightly before the cylinders above and below the horizontal have reached the vertical line. When the engine is to be reversed the arm 42 is moved to bring the valve 27 into the position indicated in Fig. 8. Consequently steam will be admitted into the cylinders above and below the horizontal before they reach the vertical line, as shown in Figs. 4 and 7. The arm 42 is provided with a spring-actuated locking member 43 which engages notches 44 provided in the bearing cover of a standard 13 and whereby the valve 27 may be retained in any desired position.

A secondary tubular valve 45 is provided within the valve 27 to control the ports 31 and 32. Said secondary valve has ports 46 and 47 registering with the ports 31 and 32 respectively. The secondary valve carries a yielding member or spring 48 opposite the ports thereof with the ends of said yielding member projecting through the ports and lying at the ends of said ports. The ends of said yielding members 48 normally tend to project out of the coöperating port of the valve 27. The ends of said ports 31 and 32 are biased to facilitate the movement of the end of the yielding member 48 when said secondary valve is revolved therein by a milled head 49 provided on the projecting end of a rod 50 which extends from the secondary valve. By rotating the secondary valve the size of the admission ports 30 and 31 may be varied and thereby the expansion of the motive fluid controlled. The yielding member 48 serves as friction locking means for retaining the two valves in the desired relative position, and also closes a small passage in 32 when 47 is moved to shorten the ports.

The displacement of the pistons by the motive fluid is transformed into rotary movement of the cylinders by the connecting rods, circular tracks, and the eccentric strap. The revolving mass is preferably inclosed in a housing 51 which revolves with the cylinders. The housing has a plurality of apertures 52 at the periphery thereof which lead into a circular conduit 53 which has a drain 54 at the lowest point thereof. Lubricant is supplied to the bearings 12 through which it is carried by suitable grooves through the lower part of the eccentric 14, dripping on to the eccentric strap 15. Centrifugal force drives the oil through the connecting rod and crosshead to the other moving parts of the engine. The excess of oil which is thrown against the periphery of the casing passes to the conduit 53 from where it escapes through the drain.

I claim:

1. In a rotary engine, a tubular shaft, a plurality of cylinders mounted to rotate with the shaft, means for supplying motive fluid to the shaft, means for distributing the fluid to the cylinders, a piston in each cylinder, a rod for each piston, a stationary eccentric for said shaft, an eccentric strap, a connecting rod from each piston to the strap, and means revoluble with the cylinders for guiding the movement of the connecting rods at the strap, and means for distributing the fluid to the cylinders including means for controlling the exhaust from the cylinders through the shaft. 70

2. In a rotary engine, a tubular shaft, a valve casing revoluble therewith, cylinders on said valve casing, means for supplying fluid to the valve casing through said shaft, a tubular valve in said casing having admission and exhaust ports, said valve casing having passages leading to both ends of the cylinders, said passages adapted to register with the admission and exhaust ports of the valve when the valve casing is rotated, a piston in each cylinder, a rod for each piston, a stationary eccentric for said shaft, an eccentric strap, a connecting rod from each piston rod to the strap, and means revoluble with the cylinders for guiding the movement of the connecting rods at the strap. 80

3. In a rotary engine, a tubular shaft, a valve casing mounted to revolve with the shaft, cylinders on the casing to revolve therewith, a tubular valve in the casing projecting out of the tubular shaft, said valve having admission and exhaust ports, said casing having passages to both ends of each cylinder, said passages adapted to register with the ports of the valve when the casing is rotated, means for supplying motive fluid to the valve, means for turning the valve whereby the admission of motive fluid to the cylinders may be varied and thereby the direction of rotation of the engine controlled, a piston in each cylinder, a rod for each piston, a stationary eccentric on the shaft, an eccentric strap, a rod connecting each piston rod to the strap, and means revoluble with the cylinder for guiding the movement of the connecting rods at the strap. 100

4. In a rotary engine, a tubular shaft, a plurality of cylinders mounted to rotate with the shaft, means for supplying motive fluid to the shaft, means for distributing the fluid to the cylinders, a piston in each cylinder, a rod for each piston, a stationary eccentric on said shaft, an eccentric strap, a rod connecting each piston rod to the strap, a roller at the connection of the rods with the strap, and a circular track for each roller revoluble with the cylinders, said track having a diameter substantially equal to the piston displacement, said means for 110

130

distributing the fluid to the cylinders including means for controlling the exhaust from said cylinders through the shaft.

5. In a rotary engine, a tubular shaft, a plurality of cylinders mounted to rotate on the shaft, means for supplying motive fluid to the shaft, means for distributing fluid to the end of the cylinders, a piston in the cylinder, a rod for each piston, a crosshead 10 at the extremity of each rod, guides for each crosshead, a stationary eccentric on said shaft, an eccentric strap, a connecting rod from each crosshead to the strap, a roller at the connection of the connecting rods 15 with the strap, and a member revoluble with the shaft having circular tracks, one for each roller, said means for distributing the fluid to the cylinders including means for controlling the exhaust from said cylinders 20 through the shaft.

6. In a rotary engine, a tubular shaft, a plurality of cylinders mounted to rotate with the shaft, means for supplying motive fluid to the shaft, means for distributing the 25 fluid to the ends of the cylinders, a piston in each cylinder, a rod for each piston, guiding means for each rod, a stationary eccentric on said shaft, an eccentric strap, a connecting rod from each piston rod to the strap, 30 and means revoluble with the cylinders for guiding the movement of the connecting rods at the strap, said means for distributing the motive fluid to the cylinders including means for controlling the exhaust from 35 the cylinders to the shaft.

7. In a rotary engine, a tubular shaft, a valve casing mounted to revolve with the shaft, cylinders on the casing to revolve therewith, a tubular valve in the casing projecting out of the tubular shaft, said valve having admission and exhaust ports, said valve having passages to both ends of each cylinder, said passages adapted to register with the ports of the valve when the casing 45 is rotated, means for supplying motive fluid to the valve, a secondary valve in the first valve, said secondary valve having admission ports registering with the admission ports of the main valve, means for revolving 50 said secondary valve within the main valve whereby the size of the ports in the main valve may be varied, yielding means carried by the secondary valve for engaging the main valve whereby the two valves may be 55 frictionally locked, a piston in each cylinder, and motion-transmission means from the pistons to the shaft to transform the reciprocating motion of the piston into rotary motion of the shaft.

8. In a rotary engine, a tubular shaft, a valve casing mounted to revolve with the shaft, cylinders on the casing to revolve therewith, a main tubular valve in the casing projecting out of the tubular shaft, said valve having admission ports and exhaust 65 ports, a partition separating the admission from the exhaust ports, said casing having passages at both ends of each cylinder, said passages adapted to register with the ports of the valve when the casing is rotated, 70 means for supplying motive fluid to the valve end leading to the admission ports, means for turning the valve within the casing whereby the admission of motive fluid to the cylinders may be varied and thereby 75 the direction of rotation of the engine controlled, a secondary tubular valve in the main valve between the partition and the motive fluid supply, said secondary valve having ports adapted to register with the 80 ports in the main valve, means for turning the secondary valve in the main valve whereby the size of the ports in the main valve may be varied, yielding members on the secondary valve engaging the main valve 85 frictionally whereby the secondary valve is prevented from accidental displacement within the main valve, a piston in each cylinder, and motion-transmission means from the pistons to the shaft to transform the reciprocating movement of the pistons into 90 the rotary movement of the shaft.

9. In a rotary engine, a tubular shaft, a plurality of cylinders mounted to rotate with the shaft, means for supplying motive 95 fluid to the shaft, means for distributing the fluid to the cylinders, a piston in each cylinder, a rod for each piston, an eccentric, and a connecting rod from each rod to the eccentric, and means for distributing the 100 fluid to the cylinders including means for controlling the exhaust from the cylinders to the shaft.

10. In a rotary engine, a tubular shaft, a valve casing revolving therewith, cylinders 105 on said valve casing, means for supplying fluid to the valve casing through said shaft, a tubular valve in said casing having initial and exhaust ports, said valve casing having 110 passages leading to both ends of the cylinders, said passages being adapted to register with the admission and the exhaust ports of the valve when the valve casing is rotated, a piston in the cylinder, a rod for each piston, an eccentric on the shaft, and a connecting rod from each rod to the eccentric. 115

AXELL WATTERBERG.
